US0D1062616S

(12) **United States Design Patent** (10) **Patent No.:** **US D1,062,616 S**
(45) **Date of Patent:** **** Feb. 18, 2025**

(54) **ELECTRIC VEHICLE CHARGER**

(71) Applicant: **NIO TECHNOLOGY (ANHUI) CO., LTD**, Hefei (CN)

(72) Inventors: **Fan Wu**, Shanghai (CN); **Xiaotian Zhao**, Shanghai (CN); **Zilin Chen**, Shanghai (CN); **Kechao Li**, Shanghai (CN); **Kris Tomasson**, Munich (DE); **Colin Phipps**, Shanghai (CN); **Shiyi Hang**, Shanghai (CN); **Guangtao Wu**, Shanghai (CN); **Xiang Zhang**, Shanghai (CN); **Yue Zhu**, Shanghai (CN)

(73) Assignee: **NIO TECHNOLOGY (ANHUI) CO., LTD**, Hefei (CN)

(**) Term: **15 Years**

(21) Appl. No.: **29/840,202**

(22) Filed: **May 26, 2022**

(30) **Foreign Application Priority Data**

Nov. 26, 2021 (CN) 202130782365.5

(51) LOC (15) Cl. **13-02**

(52) U.S. Cl.

USPC **D13/107**
